United States Patent Office.

SETH R. AND GEORGE W. BALLARD, OF COLDWATER, MICHIGAN.

Letters Patent No. 62,921, dated March 19, 1867.

IMPROVEMENT IN CARDING ENGINES.

The Schedule referred to in these Letters Patent and making part of the same.

TO ALL WHOM IT MAY CONCERN:

Be it known that we, SETH R. BALLARD and GEORGE W. BALLARD, of the city of Coldwater, in the county of Branch, in the State of Michigan, have invented certain new and useful Improvements in a Machine for Carding Wool into a continuous roll for spinning, for domestic purposes, and the following is a full, clear, and exact description of the same, reference being had to the accompanying drawings, making a part of this specification, in which—

Figure 1 represents our improvements in a side view attached to a broken-off section of a common wool-carding machine.

Figure 2 represents an end view of the same apparatus as attached.

Figure 3 shows a plan or top view of the mechanism for making continuous rolls.

Figure 4 shows a top view of the mechanism for moving the guides to run a continuous roll on to a bobbin.

Figure 5 is a view of a revolving tube (full size) constructed so as to be adjustable to vary the size of the rolls in carding different qualities of wool.

The object of our invention is to produce continuous rolls of carded wool for hand spinning in families, for domestic use, thereby greatly facilitating the operation, and making a superior quality of yarn, there being no uneven or weak places, as is the case when spinning the ordinary machine-carded, short rolls, at every place where the rolls are joined together.

Our invention consists in the construction of the rotating tubes, they being made with a recess in their outward ends, into which removable conical points, having bores of different sizes, are fitted and secured with set-screws, so that by simply substituting one of these tips or points for another the size of the "rolls" may be varied in carding to suit the different qualities of wool without removing the rotating tubes or disturbing the belt that drives them, thereby saving much time and delay in carding for customers. Our invention further consists in the arrangement and combination of the mechanism for rotating a series of tubes, and producing the lateral motion to the guides for depositing the continuous "rolls" on the bobbins so that they can be safely handled.

To enable others skilled in the art to make, apply, and use our invention, we will proceed to describe it in detail, referring to the several figures in the drawings, and to the letters of reference marked thereon.

To the plates A A of the frame of a common carding machine, on the ends which extend out from the doffer B, we bolt two pieces of hard wood, C C, of sufficient length to support the table D, on which the revolving tubes a a a are mounted in their supports b b, so that any desired number of them can be driven to operate by one belt E E driven by the pulley d. In front of the funnel ends of the tubes a is the protecting board F, it being secured to the table D, the board having smooth round openings through it, corresponding with the funnel ends of the tubes a a a, to admit the slivers after they come off the doffer B. The slivers are slightly twisted by the revolving tubes while passing through them, and they then pass between the draught rollers e e e, and also between the guide pins f f f to the bobbins, which rest upon and are revolved by frictional contact with the cylinders I I I; the traversing guide mechanism as it moves laterally, delivering the "rolls" alternately from end to end of the bobbin as usual. The protecting board F will prevent the rolls (in case one of them breaks) from being caught and tangled up by the other rolls as they are entering the tube to form the continuous "roll." The tubes have removable points, h h h, that are made separate and provided with sleeves g g, which are fitted into the socket j in the end of the revolving tube a, and are secured by a set-screw, k, so that the points h h can be easily taken out of the tubes, and others of various-sized openings inserted to produce a roll of any given size, as may be desirable in carding different qualities of wool. The movable points or sockets h h are made tapering inside, and cone-shaped on the outside, so as to bring the points to a sharp edge where it delivers the "roll" directly between the draught-rollers e e e, thereby retaining the twist in the "roll," and also dispensing with vibratory condensing rollers heretofore used for the purpose. The bobbins on which the continuous "roll" is wound are placed so as to rest on the rollers I I, the bobbin journals being in the bearings i i i in the arms m m, so as to be filled as they are revolved by the cylindrical rollers I I. The mechanism which rotates the tubes a a a, and gives lateral motion to the guides f f f, is placed upon an independent base, G, with upright posts P P; in which are the bearings of the shaft H, on which is a bevel-gear,

q, to drive the pulley *d*, to rotate the tubes *a a a* of any desired number, by a single belt, *F*, which passes over the adjustable friction-roller *r*, which operates as a tightener to the belt as it passes zigzag over one tube and under another alternately for twisting the "rolls." The guide frame *K* has a uniform laterally reciprocating movement for conveying the "rolls" on to the bobbins, which is effected by the vertical piece *L* secured to the sliding-bar *l*, on which is a finger, *o*, bearing upon the heart-shaped cam *Q*, which derives its motion by a pinion, *s*, working in a worm or screw, *t*, on the end of the horizontal shaft *H*. Thus it will be seen that there are many and very great advantages in having wool carded into continuous "rolls" for hand spinning for domestic use, over the old process of making the short rolls. In the first place, full one-half of the time and labor is saved, enabling the operator to produce twice the amount of yarn in a given time, and that of a much superior quality, as the fibre of the wool is all drawn lengthways of the "roll" giving it a better texture, greater strength, and more uniformity of size and body than it possibly can have when the rolls have to be spliced together at so short intervals. In the second place, the continuous "rolls" being wound in a compact form on bobbins, they can be handled and transported with much less liability of being injured by getting stretched or mussed up, than the ordinary short rolls in common use, which have to be picked out singly and joined together for spinning, and unless the greatest care is taken in making the splice, the yarn spun from the short rolls will be uneven and have weak places, which cannot occur in yarn spun from our improved mode of making continuous rolls and spinning them off from the bobbins which are placed in frames which are so constructed that they may be set up in any convenient warm place for spinning in cold weather.

Having thus fully described our invention, what we claim as new and useful, and desire to secure by Letters Patent, is—

1. The rotating tubes *a a a* having removable tips or points *h*, when the same are constructed and operate as described for the purpose specified.
2. We claim the arrangement of driving pulley *d*, single belt *E*, friction-roller, belt tightener *r*, and a series of rotating tubes *a a a*, in combination with worm-gear *s t*, heart cam *Q*, finger *o*, lever and slide *L l* for moving the guide frame *K*, as described for the purposes specified.

SETH R. BALLARD,
GEO. W. BALLARD.
